UNITED STATES PATENT OFFICE.

JOHN CURRY, OF NEW ORLEANS, LOUISIANA, ASSIGNOR OF ONE-FOURTH
TO WILLIS P. SWEATMAN, WILLIAM RICE, AND BARNEY FAGAN, ALL
OF NEW YORK, N. Y.

EQUIPMENT FOR THEATRICAL STAGES.

SPECIFICATION forming part of Letters Patent No. 364,221, dated June 7, 1887.

Application filed March 12, 1887. Serial No. 230,672. (No model.)

To all whom it may concern:

Be it known that I, JOHN CURRY, a citizen of the United States, residing at New Orleans, in the parish of Orleans and State of Louisiana, have invented certain new and useful Improvements in Equipments for a Theatrical Stage; and I do declare the following to be a full, clear, and exact description of the invention, such as will enable others skilled in the art to which it appertains to make and use the same.

This invention relates to an improvement applicable to theatrical stages, wherein it is desired to produce an effective representation of an act or any part of an act. It has especial relation to what is known as a "negro minstrel" stage, the object of which is to surprise and at the same time amuse an audience.

The improvement which I have made will be fully understood from the following description, when taken in connection with the annexed drawings, in which—

Figure 1 is a plan view illustrating the wire connections between the several electric lights on the seat-backs and a common source of electricity, and Fig. 2 is a diagram illustrating in plan view the wire-connections between these several electric lights on the seat-backs and a common source of electricity. Fig. 3 is a vertical section through one of the hinged-back chairs provided with an electric lamp.

Before describing my improvement, I desire to state that I do not confine myself to any definite number of chairs arranged as I shall hereinafter explain, nor to any specified means for lighting the lamps on the said chairs simultaneously, as the gist of my invention consists, essentially, in a gang or series of seats arranged in concentric order, and each individual chair having an electric lamp applied to its back above the head of the performer.

Referring to the annexed drawings by letters, A indicates a chair, stool, or seat, which may be secured to the floor of a theatrical stage, B, and which is provided with a back, C, of the form of a clover-leaf or any other suitable shape of an ornamental character. This back C is hinged to the body of the seat in such manner that it (the back) can be folded down over the seat horizontally, when desired,

for a purpose hereinafter explained. At a 50 suitable point on the front side of the back C, when it is erected, I attach an electric lamp of the arc or incandescent kinds, as may be desired. This lamp is indicated in the several figures by reference-letter D. The seats thus 55 constructed are arranged for obtaining the best effect in the following order, to wit: In rear of the proscenium or stage curtain I locate a front concentric tier, E, of seats A, which are the lowest. In rear of this tier of seats I locate another tier, F, of seats, which are higher than the front tier, and which are so arranged that the front seats are in lines between the spaces between the rear tiers of seats and in close relation thereto. In this manner I may 60 build up tier after tier of seats, forming a complete bank of seats continued back to the last and highest tier. The hinged backs of the several seats are made higher than the heads of the performers, and the electric lights are so 65 arranged on the respective seats that the rays 70 shine over the heads of the performers, and not only afford a brilliant light for them, but produce a beautiful and novel effect to the audience. All of these electric lights are suitably 75 connected by wires with a common source of electricity which is located outside of the stage and put under the control of the stage-manager. The said wires should preferably be in 80 communication with a single key, so that the lights can all be ignited simultaneously after 85 the players have taken their seats by a single touch of the said key.

In practice the wires leading from the lamps will be properly insulated and left slack on the 85 chair-backs, to allow these backs to be folded and erected, as above described.

Now, my object of hinging the chair-backs is that they may all be folded forward out of the way of the performers while entering between the chairs on their way to take their seats. Each chair-back is erected by the occupant of his or her chair before the electric lights are ignited. When all of the performers are seated, at a given signal the key aforesaid is touched and the lights on the backs of the chairs are ignited simultaneously.

In combination with the above-described

bank of separately electric-lighted chairs, I 5
may arrange at suitable places between the
chairs, or in front or back of them, artificial
flowers provided with electric lights for the
purpose of illuminating them at the same time
that the lights on the backs of the chairs of
the performers are ignited.

It is obvious that by modifying the current
of electricity the degree of brilliancy of the
lights can be regulated for the purpose of pro-
ducing different effects of light.

Having described my invention, I claim—

1. For the purpose described, a chair hav-
ing a forwardly-folding back provided with an
electric light, as specified.

2. A series of chairs of different heights ar-
ranged on a stage in tiers forming a bank,
each chair provided with an electric lamp, and
all of such lamps electrically connected with a
common generator of electricity through the
medium of a switch-key, substantially as de-
scribed.

3. A theatrical stage consisting of a bank
of seats, arranged as described, each seat hav-
ing a folding back, and each seat-back hav-
ing an electric lamp applied to it, in combina-
tion with loosely-connected insulated wires
communicating with a generator of electricity,
substantially as described.

4. The combination, with a seat or chair 30
having a forwardly-folding or hinged back, of
an electric lamp applied to the back, and an
insulated wire establishing electrical commu-
nication between said lamp and a generator
of electricity, said wire being slackly applied
to said seat to allow the folding of the back
thereof, substantially as described.

In testimony whereof I affix my signature in
presence of two witnesses.

JOHN CURRY.
